METALLIC SHEET ROOFING

Original Filed April 19, 1934

UNITED STATES PATENT OFFICE

2,005,218

METALLIC SHEET ROOFING

Oliver G. Burris, Anderson, S. C., assignor of forty one-hundredths to E. P. Vandiver and forty one-hundredths to John C. Taylor, both of Anderson, S. C.

Application April 19, 1934, Serial No. 721,384
Renewed May 1, 1935

3 Claims. (Cl. 108—17)

My invention relates to improvements in metallic sheet roofing.

An important object of the invention is to provide a metallic sheet roofing element or shingle so constructed that it may be securely attached to the roof without the employment of separate attaching elements or clips, and which will interlock with a companion element or shingle for forming a water-tight joint.

10 A further object of the invention is to so construct the roofing element or shingle that it may be quickly and conveniently moved into interlocking relation with the companion elements or shingles.

15 A further object of the invention is to provide means to collect and drain any water which may possibly pass the locking joints of the assembled elements or shingles, preventing the same from passing into the roof.

20 Other objects and advantages of the invention will be apparent during the course of the following description.

In the accompanying drawing, forming a part of this specification, and in which like numerals are employed to designate like parts throughout the same,

Figure 1 is a plan view of a plurality of assembled roofing elements or shingles,

Figure 2 is a transverse section taken on line 30 2—2 of Figure 1,

Figure 3 is a fragmentary perspective view of a pair of companion shingles, showing the same partly separated prior to having their meeting ends completely assembled,

Figure 4 is a similar view, the meeting ends being completely assembled,

Figure 5 is a fragmentary perspective view of one end of one interlocking rib or bead,

Figure 6 is a similar view of the opposite end 40 of the rib, and,

Figure 7 is a bottom plan view of the end of the other interlocking rib of the same shingle.

In the drawing, wherein for the purpose of illustration is shown a preferred embodiment of my invention, the numeral 10 designates a metallic roofing element or shingle, formed of sheet metal or the like, which may be suitably resilient. This metallic shingle is provided at one longitudinal edge with a hollow rib or bead 11, which is preferably circularly curved in cross-section, and open at its ends and one side, affording a longitudinal passage 12. This rib 11 is substantially semi-cylindrical and extends above the shingle 10 and has its open side arranged innermost with respect to the shingle, so that the pas-

sage 12 is adjacent to the shingle. The hollow rib or bead 11 is formed by bending the material of the sheet 10 upon itself in an inward direction, forming an inner layer or sheet 13, and then bending the sheet upon the edge 14, back upon itself in an outward direction affording an outer sheet or layer 15, preferably snugly engaging the inner layer or sheet 11. The outer layer or sheet 15 is continued to a point substantially opposite the passage 12, and is then bent horizontally to afford an attaching extension or flange 16, flush with the sheet 10 or body portion of the shingle. This attaching extension has its rear end terminating with the rear end of the shingle and forming a straight angle therewith, while its forward end is foreshortened and spaced from the forward end of the shingle and parallel therewith. This attaching extension or flange 16 is provided with an upwardly bulging rib 17, coacting with the hollow rib or bead 11, to afford a draining trough, for any water which may possibly pass over the hollow bead or rib 11. The attaching extension or flange 16 is preferably equipped with openings 18, for receiving nails or the like.

The upper or rear end of each hollow bead or rib 11 is cut through both layers 13 and 15 to provide an inclined or diagonal edge 19, which extends from the edge 14 to the free end of the rib and the attaching extension 16. The forward or lower end of the hollow rib or bead 11 is so modified that it is readily insertable into the upper or rear end of the hollow rib or bead 11 of a companion shingle. At its forward or lower end, the hollow rib or bead 11 has its outer layer 15 cut away and removed, the cutting affording an inclined or diagonal edge 20, which extends from the longitudinal edge 14 to a point 21, which is spaced vertically from the attaching extension or flange 16, affording a substantially vertical shoulder 22, leading to the edge 23 of the attaching extension or flange 16 which is spaced rearwardly a substantial distance from the lower or forward end of the shingle 10, as shown. The upper layer 15 is also cut from the lower layer 13 along the edge 14 from the end of the diagonal edge 20 to the free end of the inner layer 13. The inner layer 13 which projects outwardly and forwardly beyond the upper layer 15 is tapered, forming an extension 13', decreasing diameter forwardly or downwardly so that it may be readily inserted within the upper end of the companion hollow rib or bead. The edge portion 14 of the inner layer 13 remains parallel with the shingle 10, as shown.

The opposite edge of the shingle 10 is bent to

provide a hollow rib or bead 24, projecting above the shingle, and having its lower edge 25 substantially flush with the lower surface of the shingle, and spaced therefrom, for affording a passage 26. The lower or forward end of the bead 24 is cut away from a point 27, to the free edge of the bead or rib, affording a diagonal edge 28.

In assembling the shingles the lowermost shingle 10 in one upstanding row is first placed upon the roof adjacent to the lower edge of the roof so that the shingle shall suitably project below this lower edge and may be properly attached to the lower edge of the roof. The next shingle 10 in the same row is now placed above the first shingle, with the tapered inner layer extension 13' arranged lowermost. This next companion shingle to be placed in position may be slightly transversely inclined and the upper end of the bead 24 of the lowermost shingle will be guided into the lower end of the bead 24 of the companion upper shingle, by virtue of the diagonal edge 28. After the insertion has been started the next upper shingle is swung down to a flat position upon the upper end of the lowermost shingle, and the tapered extension 13' will now enter the upper end of the rib 11. The uppermost shingle is now moved downwardly, and its attaching extension or flange 16 is brought over the upper end of the attaching extension or flange 16 of the companion shingle whereby these ends overlap, the diagonal edge 19 extending behind the edge of shoulder 22, as clearly shown in Figure 4. The downward movement is continued until the edge 20 engages the edge 19. It is thus seen that the adjacent ends of the extensions or flanges 16 overlap, the shoulder 22 overlaps a portion of the edge 19, and the tapered extension 13' underlaps the meeting edges 19 and 20. An exceedingly tight joint is therefore afforded. In laying the next row of shingles the hollow rib or bead 24 is passed over the assembled ribs or beads 11 and the shingle is moved downwardly to break joint with the overlapped ends of the assembled shingles in the completed row. The next shingle in the second row is applied in a similar manner so that its lower end will overlap the upper end of the companion shingle in the same row. The extensions or flanges 16 in each row are nailed to the roof. The row of shingles next to the end of the roof is cut off and bent over the edge of the roof and nailed thereto. It is thus seen that the shingles are securely attached to the roof without the use of separate clips. The rib 17 coacts with the rib 11 for providing a trough to conduct away any water which may possibly pass the assembled parts 11. The particular advantage in my construction is that the attaching extensions or flanges are permanently secured to the shingles and will therefore, be readily nailed to the roof. Where detachable clips are used, workmen frequently fail to use a sufficient number of these clips, whereby the shingles are not securely attached to the roof. The use of attaching extensions or flanges 16 involves a considerable problem in the assembling of the shingles in the same row. In the patent to E. E. Barker, 381,318, an attempt has been made to solve the problem. This construction is not wholly satisfactory as the joint produced is not sufficiently tight. In this patent the meeting ends of the attaching flanges cannot overlap, but simply abut, and further, the outer layer is entirely cut away and the inner layer is partly cut away. In my construction the inner layer is not cut away but is rendered tapered, and

the outer layer is cut on a diagonal to the point 21, affording a shoulder 22. In my construction the edge 19 extends behind this shoulder and the extensions 16 overlap, and further the meeting edges 19 and 20 are spanned by the complete inner layer 13. A much tighter joint is effected.

It is to be understood that the form of my invention herewith shown and described, are to be taken as preferred examples of the same, and that various changes in the shape, size and arrangement of parts may be resorted to without departing from the spirit of the invention, or the scope of the subjoined claims.

Having thus described my invention what I claim is:

1. A metallic shingle having its material at one longitudinal edge bent inwardly over the same for affording a longitudinal hollow bead, said bead having inner and outer layers and an inner longitudinal edge spaced from the upper surface of the shingle for affording a longitudinal passage, an attaching extension carried by the outer layer and disposed generally in the plane of the shingle, the forward end of the attaching extension being foreshortened with its forward end spaced from the forward end of the shingle and being substantially parallel therewith, said bead at its rear end having its inner and outer layers cut for affording a diagonal edge extending from the inner longitudinal edge of the bead to the free end of the same, said bead having its outer layer near its forward end cut away for providing a diagonal edge which extends from the longitudinal edge of the bead to a point spaced a substantial distance above the attaching extension for providing a substantially vertical shoulder extending from this point to the forward foreshortened end of the attaching extension, the inner layer of the bead projecting forwardly beyond this diagonal edge of the outer layer to provide a bead extension terminating at the forward end of the shingle and tapering rearwardly, said shingle being provided at its opposite longitudinal edge with a hollow rib projecting above the shingle and having its free longitudinal edge spaced from the shingle for affording a longitudinal passage, the forward end of this rib being cut to afford a diagonal edge.

2. A metallic shingle having its material at one longitudinal edge bent inwardly over the same for affording a longitudinal hollow bead, said bead having inner and outer layers and an inner longitudinal edge spaced from the upper surface of the shingle for affording a longitudinal passage, an attaching extension permanently secured to the outer layer and having its rear end foreshortened and spaced from the rear end of the shingle, said bead at its rear end having its inner and outer layers cut away for affording a diagonal edge extending from the inner longitudinal edge of the bead to the free end of the same, said bead having its outer layer near its forward end cut away for providing a diagonal edge which extends from the free longitudinal edge of the bead to a point spaced a substantial distance above the attaching extension for providing a substantially vertical shoulder extending from this point to the forward foreshortened end of the attaching extension, the inner layer of the bead projecting forwardly beyond this diagonal edge of the outer layer to provide a bead extension terminating substantially at the forward end of the shingle, said shingle being provided at its opposite longitudinal

nal edge with a hollow rib projecting above the shingle and having its free longitudinal edge spaced from the shingle for affording a longitudinal passage.

5 3. A metallic shingle having its material at one longitudinal edge bent over the same for affording a longitudinal hollow bead, said bead having inner and outer layers and an inner longitudinal edge spaced from the upper surface of 10 the shingle for affording a longitudinal passage, an attaching extension permanently secured to the outer layer and having its forward end foreshortened and spaced from the forward end of the shingle, said bead having its outer layer near 15 its forward end cut away for providing a transverse edge, the upper portion of the transverse edge projecting forwardly beyond the lower portion of said transverse edge and such lower portion forming a substantially vertical shoulder, 20 the inner layer of the bead projecting forwardly

beyond the transverse edge of the upper layer to provide a bead extension terminating substantially at the forward end of the shingle, the rear end of said bead having its upper portion terminating short of the rear end of the shingle and its lower portion extending rearwardly beyond the upper portion, the arrangement being such that the forward end of the attaching extension of the shingle may be arranged over the rear end of the attaching extension of the next forward shingle and said lower portion of the rear end of the bead of such forward shingle will pass beneath the substantially vertical shoulder of the next rear shingle affording an overlapping arrangement, said shingle being provided at its 15 opposite longitudinal edge with a hollow rib projecting above the same and having a longitudinal edge spaced from the shingle for affording a longitudinal passage.
